US0D1077729S

(12) **United States Design Patent** (10) **Patent No.:** **US D1,077,729 S**
(45) **Date of Patent:** **** Jun. 3, 2025**

(54) **MOBILE POWER SUPPLY**

(71) Applicant: **Shenzhen taiyouwenhua Technology Co., LTD**, Shenzhen (CN)

(72) Inventor: **Renlin Sun**, Shenzhen (CN)

(73) Assignee: **Shenzhen taiyouwenhua Technology Co., LTD**, Shenzhen (CN)

(**) Term: **15 Years**

(21) Appl. No.: **29/902,414**

(22) Filed: **Sep. 13, 2023**

(51) **LOC (15) Cl.** **13-02**

(52) **U.S. Cl.**

USPC **D13/103**; D13/107

CLAIM

The ornamental design for a mobile power supply, as shown and described.

DESCRIPTION

FIG. 1 is a front perspective view of a mobile power supply, showing my new design;

FIG. 2 is a rear perspective view thereof;

FIG. 3 is its split state diagram;

FIG. 4 is a front view thereof;

FIG. 5 is a rear view thereof;

FIG. 6 is a top view thereof;

FIG. 7 is a bottom view thereof;

FIG. 8 is an enlarged elevation view of the left side; and,

FIG. 9 is an enlarged elevation view on the right side.

1 Claim, 9 Drawing Sheets
